OIL TANK FILLING ALARM

Michael Geller, Toronto, Ontario, Canada

Application August 14, 1952, Serial No. 304,243

10 Claims. (Cl. 116—110)

This invention relates to a device designed to signal when a tank or like closed vessel associated therewith is being filled, the cessation of the signal denoting the tank to have been filled at least to a predetermined level. Such devices are especially useful in those locations where the tank itself is not readily accessible for visual inspection and/or where it must be filled from a remote point through a conduit. Situations of this nature are frequently found in oil heating installations, for example, where the oil storage tank is located in the cellar of a building adjacent the heating plant and is filled from the exterior of the building through a pipe.

Specifically, the invention visualizes an indicating element which automatically signals when the tank is being filled. Also contemplated is means for incapacitating said indicating element; the incapacitating means being operable by a level responsive element which may be a float, for example. The indicating element goes into operation as soon as the filling of the tank commences and continues its operation until the level of the tank contents has reached a height, predetermined by the relative location of the float at which time the float will commence to act to set the signal incapacitating means into operation to procure the cessation of the signal, thereby indicating that the tank has been sufficiently filled.

Such indicating element may be of the sonorous type and may be actuated by the gases displaced from the tank by the entering liquid. This indicating element or whistle is preferably installed in a conventional venting circuit which also leads to the exterior of the building, usually to a point adjacent the fill pipe. Thus, without leaving the filling position an operator, noting the signal, will continue filling the tank until the cessation thereof denotes the tank to have been adequately filled.

While the broad idea of a signalling device for the purposes herein visualized is not new, the principle object of the invention is to provide an improved device of this character which is economical to make, positive in action, and simple to install particularly in an existing system not already equipped therewith.

A further object of the invention is to provide a device of this character whose parts are normally arranged to direct and permit the vented gases to pass through and actuate the associated indicating element; one at least, of the said parts being movable to preclude the vented gases from actuating the said indicating element.

A still further object of the invention is to provide a device of this character in which a level responsive means is employed for disturbing the relationship of the parts to procure the cessation of the signal under appropriate circumstances.

A still further object of the invention is to provide a device of the character above described wherein the movement of the part or parts causing the cessation of the signal will automatically provide an alternative escape opening for the vented gases and thereby prevent increased gas pressure from developing within the tank as a result of over-filling.

It is a still further object of the invention to provide a signalling device of the present character having breathing facilities to enable the liquid contents to be withdrawn from the tank even when it is over-filled without tending to create a vacuum.

The foregoing and other objects of the invention which will hereinafter appear are attained by means of the constructions hereinafter described and illustrated in the accompanying drawings in which:

10 Fig. 1 is a small scale isometric view of a tank installed in the basement of a building and having a vent and fill piping which extends through the basement wall to the exterior; the invention being included in the vent circuit.

15 Fig. 2 is an enlarged side elevational view of the invention mounted in the upper portion of the tank, which latter is sectioned.

Fig. 3 is a top plan view of the invention with certain parts removed therefrom.

20 Fig. 4 is a section along the line IV—IV in Fig. 2 illustrating the normal relationship of the parts, i. e. when the tank is less than full.

25 Fig. 5 is a view similar to Fig. 4 illustrating the relationship of the parts when the tank has been filled to the predetermined level, and

Fig. 6 is a view similar to Figs. 4 and 5 illustrating the relationship of the parts when the tank has been filled past the predetermined level or overfilled.

30 In the drawings like numerals of reference indicate corresponding parts in the different figures.

As suggested by the brief descriptions of the drawings, three conditions of the tank are visualized:

(a) The normal or under-filled condition illustrated in Fig. 4,

35 (b) The filled condition illustrated in Fig. 5, and
(c) The over-filled condition illustrated in Fig. 6.

As shown in the attached drawings the embodiment of the invention selected for exemplary purposes includes the open-ended tubular fitting 1 which is designed to be installed as an element in the vent circuit which is comprised of the vent opening 2 at the top of the tank 3 and the piping 4 leading therefrom to the exterior atmosphere. Below the threading 5 by means of which it may be installed in the vent opening 2, for example, the fitting 1 has a skirt 6 which narrows or converges at the bottom to form a valve seat 7. Spider arms 8—8 curve downwardly from the valve seat 7 to form a bearing 9 located well below and concentric with fitting 1; a top plan view of the foregoing constriction being afforded by Fig. 3.

50 Fitting 1 provides housing for the indicating element which is, in this case, the whistle 10, which has spaced upper and lower walls 11—11 with conventional central apertures 12—12 which are large enough to permit the passage of gases at the pressure normally created by the entry of liquid in the tank. The whistle 10 is held in a perimetrical mounting 13 conforming in shape and dimension to the valve seat 7 in which it is normally designed to seat.

60 It will therefore be seen that when the whistle mounting 13 is in place on the valve seat 7, the gases displaced by the filling of the tank will be able to escape only through the whistle 10 whose apertures are sufficiently large for the purpose, thus signalling that the tank 3 is being filled substantially as shown in Fig. 4. On the other hand, if the mounting is lifted off the valve seat 7 as in Fig. 6, the gases will by-pass the whistle 10 and will not cause it to sound.

The invention also visualizes a float 15 within the tank 70 3 having a stem 16 rigidly secured thereto and extending upwardly therefrom towards the fitting 1 and vertically slidable in the bearing 9. The top of the stem 16 con-

sists of a head 17 which is preferably domed and has a screw driver type of slot 18 whose purpose will duly appear. It will be obvious as shown in Figs. 4, 5 and 6 that the stem head 17 is always aligned with the somewhat smaller aperture 12 in the lower whistle wall 11 and can be raised to block it, to obstruct the flow of gas therethrough and to silence the whistle 10 substantially as shown in Figure 5. Actually, tests have shown that mere proximity of the parts is sufficient to achieve this latter result. The maximum spacing between the stem head 17 and the whistle 10 is hence required to be only enough to prevent the latter from being silenced.

Inasmuch as the float 15 is designed to be raised by the filling of the tank 3 it will be seen that lengthening or shortening the stem 16 will have the effect of silencing the whistle 10 at an earlier or later point in the filling of the tank 3. On the other hand, if the filling should be continued after the lower aperture 12 is blocked, the continued rise of the float 15 and stem 16 will merely result in the bodily lifting of the whistle 10 and its mounting 13 off the valve seat 7 as shown in Fig. 6 thus affording an escapement for the vented gases and preventing their accumulation under pressure. These two results follow each other so closely that they may be regarded as substantially simultaneous for all practical purposes.

To ensure that the mounting 13 will always remain in the central axis of the valve seat 7, arms 20—20 depending from the former meet centrally of the device to form a secondary bearing or sleeve 21 for the stem 16.

The principal advantage accruing from the mechanical lifting of the mounting 13 when the tank 3 is overfilled resides in that increased gas pressures are prevented from forming in the tank 3. Were such increased pressures allowed to arise, the gases would seek to escape through the tank-filling circuit 22 which is the only remaining port and thus blow back some of the entering liquid.

The prior art discloses related devices in which the gases vented through a whistle must first pass through a pendant tube. When the tank contents reach and seal the mouth of the tube, the whistle is consequently silenced. Continued filling in these instances merely results in the deeper immersion of the tube in the liquid. The subsequent withdrawal of the liquid is resultantly hampered by the fact that air cannot freely enter the tank to replace the evacuated liquid. This tends to create a partial vacuum which increases the load on the associated pumping system and hence deleteriously affects it.

The present invention avoids this contingency by omitting the use of this tube or any equivalent thereof and by arranging the parts so that the mounting 13 is supported in an elevated position on the float stem 16 leaving a breather opening into the tank 3 at all times when it is overfilled. As the level of the tank contents decreases, one of the first results will be the dropping of the mounting 13 back to its normal position on the valve seat 7. At this precise point the stem head 17 will still be engaged in the lower whistle aperture 12. It is to maintain these essential breathing facilities that the stem head 17 is provided with the aforesaid slot 18; air being at that time adapted to enter the tank 3 through the whistle 10, and through the said slot 18.

The conventional tank is usually formed of relatively light-gauge material with vent, fill, and other openings. Owing to the thinness of the component material, an interiorly threaded spud 23 is usually welded to the tank around each of the various openings; the purpose thereof being to provide purchase for the associated piping. Owing to the fact that various sizes of piping may be required in various localities and under various conditions the spud 23 is preferably large enough to accommodate the largest pipes; a reducing coupling (not shown) being employed to fit the requisite size of pipe to the tank.

The design of the present fitting 1, whereby all of the parts associated therewith are adapted to be contained more or less within the tank 3, enables it, the fitting 1,

5 to function much the same as a reducing coupling. Thus the installation of the present device in an existing vent circuit often involves merely its substitution for the previous reducing coupling, thereby avoiding further pipe cutting and fitting.

10 Notwithstanding that it is quite obvious, it should perhaps still be pointed out that the whistle 10 and mounting 13 can also be unseated from the valve seat 7 by mere gas pressure; independently, that is, of any lifting force applied thereto by the float and stem 15 and 16. The whistle apertures are quite adequate for venting the gases displaced at average tank-filling rates. If for 15 any reason, however, the gas pressure in the tank 3 exceeds the venting capacity of the whistle apertures, the whistle and mounting 10 and 13 will be displaced bodily by such excessive pressures to unblock the fitting 1 and permit the free escape of the gases.

The foregoing submission also places considerable 20 emphasis on the opening of a gas by-pass around the whistle 10 co-incidentally with the silencing thereof by the stem head 17. Understandably, however, the magnitude of the said by-pass is not herein contemplated to have any specific value or to be of any specific degree. Three main factors govern the magnitude of the by-pass, 25 namely: the size and density of the float 15, the specific gravity of the liquid in the tank 3, and the weight of the whistle and the mounting 10 and 13.

Notwithstanding the inadequacy of one or more of 30 these factors to effect a substantial lifting of the whistle 10, it is nevertheless true that once the stem head 17 contacts the whistle 10 it will apply an upward force thereto to open at least a minute by-pass. In addition, this action will also at least tend to reduce the effective weight of the whistle 10 whereby the gas pressure required to unseat it will be materially reduced.

35 The importance and significance of this result will be appreciated in view of the fact that once the stem head 17 blocks the whistle 10, the venting capacity of the latter will be substantially decreased if not entirely obliterated and this occurs at a stage in the filling of the tank 3 when gas pressures build rather rapidly.

Under these conditions, the fact that the opening of a 40 by-pass is facilitated as above set forth imparts an important advantage to the invention.

45 What I claim as my invention is:

1. A signalling device for the vent circuit of a liquid storage tank comprising a tubular fitting adapted to be installed in said vent circuit and to become a part thereof; a gas-operable indicating element disposed in and normally blocking the said fitting, said indicating element having apertures forming a passageway for gases; means for incapacitating said indicating element normally disposed in non-incapacitating relation thereto; a float below the indicating element; a stem rigidly secured thereto and movable therewith, and a bearing for the said stem carried by the fitting; the stem being slidable in the bearing to disturb the normal relationship of the indicating element and its incapacitating means to incapacitate the former and to substantially simultaneously open a gas by-pass around it.

50 2. A signalling device for the vent circuit of a liquid storage tank comprising a tubular fitting adapted to be installed in said vent circuit and to become a part thereof; a whistle disposed in and normally blocking said fitting and having apertures forming a passageway for gases; means for incapacitating said whistle normally disposed in non-incapacitating relation thereto; a float below the fitting; a stem rigidly secured thereto and movable therewith, and a bearing for the said stem carried by the fitting; the stem being slidable in the bearing to bring the whistle and its incapacitating means into close proximity to silence the former and to substantially simultaneously move it out of fitting blocking position.

55 3. A signalling device for the vent circuit of a liquid storage tank comprising a tubular fitting adapted to be

installed in said vent circuit and to become a part thereof; a whistle disposed in and normally blocking the said fitting and having apertures forming a passageway; a float below the whistle; a stem secured to and movable with the float, and a bearing for the stem carried by the fitting; the stem being slideable in the said bearing to block the passageway through the whistle and to substantially simultaneously move it out of fitting blocking position.

4. The signalling device disclosed in claim 3 wherein the whistle is blocked by the top of the stem which is somewhat larger than the whistle apertures and is slotted.

5. A signalling device adapted to be communicatingly installed between a liquid storage tank and a tank vent circuit comprising a tubular fitting having external tank engagement threading and internal vent pipe engagement threading both located adjacent the top of the fitting, a skirt depending therefrom and a narrowed valve seat at the bottom of the skirt; a whistle seated on said valve seat and having apertures forming a passageway; a float; a stem secured to and movable therewith; spider arms depending from the fitting and merging therebelow to form a bearing for the stem, and a slotted head at the top of the stem.

6. A signalling device for the vent circuit of a liquid storage tank comprising a tubular fitting adapted to be installed in said vent circuit and to become a part thereof; a gas-operable indicating element having apertures forming a gas-venting passageway therethrough disposed in and normally blocking said fitting, said indicating element being bodily displaceable by gas pressures exceeding the venting capacity of the aforesaid apertures to allow the gases to escape through the fitting around the said indicating element; a float disposed below the said indicating element and means controllable thereby to incapacitate the said indicating element and to substantially simultaneously apply force thereto to render it more readily displaceable by gas pressure.

7. A signalling device for the vent circuit of a liquid storage tank comprising a tubular fitting adapted to be installed in said vent circuit and to become a part thereof; a whistle having apertures forming a gas-venting passageway therethrough disposed in and normally blocking said fitting, said whistle being bodily displaceable by gas pressures exceeding the venting capacity of its apertures to allow the gases to escape through the fitting around the whistle; a float disposed below the said whistle and means controllable thereby to block the passageway through the whistle and to substantially simultaneously apply force to the latter to render it more readily displaceable by gas pressure.

8. A signalling device for the vent circuit of a liquid storage tank comprising a tubular fitting adapted to be installed in said vent circuit and to become a part thereof; a gas operable indicating element having apertures forming a gas-venting passageway therethrough disposed in and normally blocking the said fitting, said indicating element being bodily displaceable by gas pressures exceed-

ing the venting capacity of the aforesaid apertures to allow the gases to escape through the fitting around the said indicating element; means for incapacitating said indicating element normally disposed in non-incapacitating relation thereto; a float below the indicating element; a stem rigidly secured thereto and movable therewith, and a bearing for the said stem carried by the fitting; the stem being slideable in the bearing to disturb the normal relationship of the indicating element and its incapacitating means to incapacitate the former and to substantially simultaneously apply force thereto to render it more readily displaceable by gas pressure.

9. A signalling device for the vent circuit of a liquid storage tank comprising a tubular fitting adapted to be installed in said vent circuit and to become a part thereof; a whistle having apertures forming a gas-venting passageway therethrough disposed in and normally blocking the said fitting, said whistle being bodily displaceable by gas pressures exceeding the venting capacity of its apertures to allow the gases to escape through the fitting around the said whistle; means for incapacitating the said whistle normally disposed in non-incapacitating relation thereto; a float below the fitting; a stem rigidly secured thereto and movable therewith, and a bearing for the said stem carried by the fitting; the stem being slideable in the bearing to bring the whistle and its incapacitating means into proximity to block the passageway through the whistle and to substantially simultaneously apply force to the latter to render it more readily displaceable by gas pressure.

10. A signalling device adapted to be communicatingly installed between a liquid storage tank and a tank vent circuit comprising a tubular fitting engageable in an opening at the top of the tank and having a narrowed valve seat at its bottom; a whistle having apertures forming a gas-venting passageway normally seated on the valve seat to block the said fitting; said whistle being bodily displaceable by gas pressures exceeding the venting capacity of its apertures to allow the said gases to escape through the fitting around the whistle; means for coupling the vent circuit to receive the gases vented through the said fitting; whistle incapacitating means normally disposed in non-incapacitating relation thereto, and a float coupled and movable to bring the whistle and its incapacitating means into close proximity to silence the former by blocking the passageway therethrough and to substantially simultaneously apply force thereto to render it more readily displaceable by gas pressure.
